HYDRAULIC PUMP.

Application filed May 18, 1925. Serial No. 30,899.

This invention relates to hydraulic pumps of the type having one or more rotary impeller or pump elements and adapted for single or multi-stage construction for either 5 surface or deep well use, although the advantages of the invention more particularly appear when embodied in a multi-stage deep-well pump.

The invention relates more particularly to 10 a certain novel construction of the various elements in combination, the rotary impellers, diffusion members and intermediate passages or chambers, forming together the flow passages through the pump, being designed to 15 present certain novel advantages in respect to velocities and directions of flow and equalization of water pressures, and to certain novel features of the elements themselves, particularly of the impeller and diffusion members, not only adapting them for 20 their cooperative functions but securing certain novel advantages in their individual functions.

A general object of my invention is to produce 25 a high speed pump of large capacities and of high pressure head per stage with a relatively small diameter of impeller and pump casing, thus adapting the pump particularly to deep well use.

Another general object of the invention is the production of such a pump having a high speed impeller of wide range of efficiency and capacities without excessive variations required in the driving power, thus enabling 35 a reduction in the size and weight of the pump and its drive by relatively high speed motors under a fair approximation to constant power conditions throughout the range of operation of the pump.

In the operation of the pump there must, of course, be imposed on the initial stream of entering liquid, changes both in its velocity and direction of flow, first by the impeller and then in succession by the various other elements of the pump along the line of flow until the final outflow determining the net head produced by the pump is reached. In order to attain the highest possible efficiency in pumps of the general type to which this invention relates, it is essential 50 to avoid all unnecessary energy losses within the pump passages, such as those due to abrupt changes in the velocity or direc-

tion of the flowing liquid which result in surface friction, the formation of eddy currents or unequal water pressures in areas normal to the line of flow. 55

Accordingly, my invention contemplates, as one of its more particular objects, such construction or conformation, in cooperative 60 plan or relation, of the various elements forming the flow passage of the pump, as in the operation of the pump to produce the final head or pressure at the outlet by impressing upon the inflowing stream the required changes in its initial velocity and 65 direction gradually and along such lines of flow as to reduce surface friction to a minimum, avoid eddy currents and, in fact, effect equalization of water pressures throughout 70 areas normal to the line of flow.

My invention further particularly contemplates a novel impeller combining certain advantageous features of the axial and the centrifugal types, this novel impeller being 75 designed to receive the incoming liquid in substantially true axial direction and to impress thereon, by gradual increments and along certain distinct lines of flow, a radial component with the radial component increasing 80 predominating toward the outlet of the impeller, the result being a condition of true axial flow at the entrance and a combined axial and centrifugal action as the liquid passes through the impeller to the discharge. The initial axial flow has been found to be advantageous in the avoidance 85 of eddy currents in the entering stream, shock of entrance and consequent loss of energy and quantity flow. The gradual increase of the radial component and centrifugal action has been found to be particularly 90 advantageous not only in the continued unbroken and smooth flow of the water without abrupt change in its velocity or direction 95 but in improving the lifting or pumping action over the straight axial or centrifugal types.

The invention also contemplates, in the novel impeller, certain features of form and contour of impeller vanes and impeller outlet, not only effecting equalization of water pressures throughout areas normal to the line of flow of the liquid through the impeller, but also a uniform increase of energy 105 of flow from inlet to outlet on all radii of

the impeller vanes and a constant energy of flow from the impeller throughout the entire area of the delivery outlet, thus insuring an eddyless flow and the highest possible capacity and efficiency.

The invention further contemplates the provision, in association with the novel impeller, of a vaneless chamber passage for the immediate reception therein of the outflow from the impeller, with smooth-surfaced walls of a form and contour enabling the water outflowing from the impeller to find its own path under the conditions as to velocity and direction of flow imposed thereon by the impeller, without substantial increase of surface friction or formation of eddy currents. This chamber passage may, within the broader aspects of my invention, take different forms and may be used with different types of diffusers for converting the velocity of the flow into pressure, as, for instance, a volute chamber through which the liquid is delivered finally or to the next impeller.

My invention more particularly contemplates, however, the employment of this chamber passage in association with a diffusing member on its delivery side, and with the chamber passage therefor between the impeller and the diffusing member, receiving the flow from the one and delivering it to the other. And for such use, the vaneless chamber passage is formed not only to receive the flow from the impeller without substantial change in direction and velocity of that flow but also to gradually change that flow from its axial radially outward direction imparted thereto by the impeller to a somewhat inward flow, the flow whirling through the chamber under the combined axial and centrifugal action imparted by the impeller.

The novel diffusing member, also contemplated by my invention, is provided with diffusing vanes conforming in contour and in angle at their inlet edges to the line of flow from the chamber passage so as to receive the flow therefrom without change of direction. An important object of the diffusion member is to return the flow to true axial direction either for final exit from the pump or for delivery to the next impeller of the series in the multi-stage construction of the pump. Preferably also, the diffusion member is designed to effect, to some extent at least, a conversion of velocity into pressure, although this is not of primary importance in the functioning of that member. In harmony with the general plan of the various elements forming the flow passage through the pump and affecting the velocities and directions of flow, the diffuser embodies certain features of form and contour of the guiding vanes and adjacent passage surfaces, gradually impressing upon the

liquid those final changes in velocity and direction of flow which produce the axial outflow under the desired head, the lines of flow imparted to the liquid being such as to present a smooth, eddyless current of 70 constant pressure and energy of flow throughout each successive plane normal to the line of flow.

The foregoing objects and principles of my invention as well as other objects and principles thereof, will more fully appear in the description hereinafter given of a concrete embodiment of the invention in its present preferred form. It is to be understood, however, that my invention is not 80 limited in its principles to such embodiment but that other embodiments and modifications of the present one may be made within the broad principles of the invention and as defined in the appended claims. 85

The concrete illustrative embodiment of the invention referred to is shown in the accompanying drawings forming a part of this specification.

In these drawings:

Fig. 1 is a view, partly in side elevation and partly in vertical longitudinal section, of a portion of the pump, from the drop pipe downwardly, the pump illustrated being of the multi-stage deep-well type. In 95 this view the impeller blades are omitted from the sectional portion in order to show more clearly the inner contours of the impeller core and shroud ring.

Fig. 2 is a transverse sectional view 100 through the impeller and whirl chamber, on the line 2—2 of Fig. 1, looking in the direction of the arrows;

Fig. 3 is a perspective view of one of the impeller units, the view being on a scale 105 enlarged over that of Fig. 1;

Fig. 4 is a plan view, on the same scale as Fig. 3, partly broken away, of the outlet face of the impeller unit, showing the delivery opening between the delivery end 110 edges of each two successive vanes and a portion of the water-contact surfaces of two of those vanes;

Fig. 5 is a plan view, on an enlarged scale, of the delivery face of the lower diffuser unit of Fig. 1, but showing the outer casing or wall partly in section on the line 5—5 of Fig. 1, looking in the direction of the arrows on that figure; and

Fig. 6 is a perspective view of the same 120 unit with the outside casing or shell removed to show the form of the vanes.

The pump here shown for the purpose of more fully illustrating the broad principles of the invention, as well as presenting certain more detailed features found of value in practice, is of the deep-well two-stage type, having any suitable type of driving head, not necessary here to be shown, coupled to the vertical impeller shaft 10 125 130

which extends down through the drop pipe 11 and through the successive assembled units of the pump as shown in Fig. 1.

As already stated, the essential parts of 5 the novel pump acting upon the liquid to be delivered and impressing on that liquid from its initial state those characteristics of velocity and direction of flow required to insure the results aimed at by my invention, 10 are in each of the pump stages, the impeller unit, the diffuser spaced therefrom and the intermediate chamber passage receiving the water in its whirling movement of flow from the impeller and delivering that flow somewhat changed in direction to the diffuser.

The impeller units, two in number in the present illustrative pump, are indicated generally by the numeral 12 on Fig. 1, the diffuser units by the numeral 13, and the intermediate chamber passages, which because of the characteristic whirling flow of the water therethrough, may appropriately be termed whirl chambers, by the numeral 14. Inlet guide vanes 15 are preferably provided 25 on the entrance side of the lower impeller unit, to insure an initial true axial flow of the water to the impeller. The impellers 12 are mounted on the shaft 10 for rotation therewith while the diffusers 13 are 30 fixed, as shown, their hubs serving as supports for the bearings 16 of the shaft.

The impellers, diffusers and whirl chambers of the two-stages of the pump are duplicates so far as their essential parts pertaining to the invention are concerned and hence a description of one of each applies to the other of the pair. They are all shown in Fig. 1 in half section as cut by an axial plane passing through the center of the impeller shaft 10.

Viewed along the section plane of Fig. 1, the impeller may be said to comprise a central cone-shaped core portion, a half section of which is there shown, having a hub 17 extending about and secured to the impeller shaft 10 and a peripheral ring or shroud 18, spaced from the core to provide the flow passage indicated by the arrow line of flow, that passage having the axially directed inlet 19 of greater dimensions, measured in the section plane of Fig. 1, than the obliquely outward directed outlet 20, and having smooth walls of large radii of curvature between the two. The impeller blades or vanes 25 are located in the passage thus generally defined and in fact divide the passage into a plurality of passages, one between each two successive vanes. The cross-sections of any one such flow passage taken on a plurality of axial planes intersecting the passage, would, if each such cross-section were swung to the axial plane in which the sectional view of Fig. 1 is taken, and were projected thereon, present however, the characteristics just referred to.

The detailed characteristics of the impeller vanes and flow passages as embodied in the illustrative example of the novel impeller, and which example has been found in practice to constitute one very effective embodiment in attaining the objects and purposes of the invention, will more fully appear from a consideration of Figs. 2 to 4, inclusive.

Referring first to the perspective view of 75 the impeller shown in Fig. 3, it is to be noted that the impeller vanes 21 start at the inlet end 19 in a plane at right angles to the impeller shaft or axis of rotation of the impeller, their inlet edges extending in that 80 plane from the hub of the impeller in diverging curves outwardly to the annular projecting shell forming the outer boundary of the inlet. These characteristics, and particularly the bringing of the inlet edges 85 of the vanes inwardly to the impeller hub, provide large entrance capacity with a minimum of diameter of the impeller and a true axial entering flow.

As heretofore stated, an object of the invention, in the novel impeller, is to provide not only for a true axial entering flow but also for a superimposed centrifugal impeller action on the water flowing through the impeller to increase the lifting effect. Without some provision to prevent it, however, the superposition of a radial component of flow with its attendant centrifugal action by the rapid rotation of the impeller, presents very substantial energy losses and reductions 100 in outflow by reason of eddy currents developed by unequal pressure effects on the water entering near the impeller shaft and that entering near the outer edges of the inlet opening. The means which I have devised for avoiding the disadvantages mentioned comprises a contour of impeller vane surfaces from inlet to outlet ends acting upon the water to gradually decrease the axial component of flow and gradually increase 105 the radially outward component toward the impeller outlet. In the present illustrative embodiment of the invention, such means may be described as a gradual warping of 110 the vane surfaces of the impeller from a position where the entrance edges are in a plane normal to the axis at the entrance end to a position where the delivery edges are at an acute angle to any axial plane intersecting said edges at the delivery end, the 115 warping being such as to secure a uniform increase of energy throughout all areas normal to the flow. These vane characteristics are shown more particularly in Figs. 2 to 4, inclusive. In the perspective view, Fig. 3, as already mentioned, the impeller vanes 21, at the inlet end, start with their edges in a plane normal to the impeller axis. From 120 their inlet edges in the plane referred to, the vane surfaces proceed in sweeping flow

120

125

130

135

lines gradually radially outward and axially toward the outlet end or face of the impeller and with a gradually increasing inclination or warp of the vane surfaces obliquely inward, in the direction of the outlet face, toward the axis of rotation, until, as shown in Figs. 3 and 4, the outlet end edges of the vanes, indicated at 21', are presented at oblique angles to the impeller axis as on a conical surface with the slope of the surface toward the axis in the delivery direction and with the opposite terminal points of each vane, indicated by the numerals 22 and 23 in Figs. 3 and 4, on different radii, with the advance considered in the direction of the pump discharge terminal point 23 closer to the axis than the rearward one 22.

The extent of warp of the impeller vanes may be varied depending upon the size and 29 rotational speed of the impeller design of the delivery edges to an axial plane intersecting said edges, the angle at the delivery end being preferably smaller for small radial size pumps of high capacity. I have found in actual practice of the invention that an impeller having vanes conforming to the principles of surface warping here referred to, impresses upon the entering flow such a gradual increase of radially outward component as to equalize pressure effects on the water entering near the impeller shaft and that entering near the outer edges of the inlet opening, notwithstanding the centrifugal force developed by the 35 rapidly rotating impeller, and to produce uniform increase of energy from inlet to outlet on all radii and therefore with the energy uniform throughout each area or plane normal to the flow.

Other characteristics of the novel impeller additionally contribute to its capacity and efficiency, particularly for the small high speed impeller desired. In the preferred embodiment of my novel impeller, the inlet and outlet between each two successive vanes at their opposite ends sustain a definite dimensional relation to each other. The largest radius of the inlet is made to equal, approximately, the smallest radius of the outlet, this enabling the determination of the least maximum distance from the impeller axis of the inner and outer edges of the vanes which will produce a small pump capable of high speed and with maximum capacity and lifting effect. This characteristic is illustrated in Fig. 3 and by a comparison of Figs. 2 and 4. The inner surface of the inlet ring 19 shown in Fig. 3 is of approximately the same diameter as the outer edge of the cap rim 24. The largest radius of inlet opening, such as 25 in Figs. 2 and 3, extends from the impeller axis to the outer terminal or tip of the inlet edge of the vane, indicated at 26, or what amounts to the same thing, from the impel-

ler axis to the inner surface of the inlet ring 19. And the smallest radius of outlet, such as outlet 27 shown in Fig. 3, extends from the impeller axis to the inner or advanced tip of the outlet edge of the vane, indicated at 23, or, what amounts to the same thing, to the outer edge of the cap rim 24. In other words, the points 26 and 23, approximately equally distant from the impeller axis, mark the terminals referred to of those opposite edge portions of each vane extending from inlet to outlet face of the impeller, their angular displacement from each other about the impeller axis depending, of course, on the degree and extent of curvature design for an impeller of that particular diameter. Obviously the inner tips of the inlet edge of the vanes are on the outer surface of the impeller hub, as indicated at 28 in Figs. 2 and 3, and the displacement of the outer tip 22 (Figs. 3 and 4) of the outlet edge of the vane is determined by the extent of warp of the vane surface from the inlet end to the delivery end desired or required for the size of the pump and its maximum efficiency under the principle of warping the vanes already referred to. Between these terminals at the inlet and outlet edges of the vanes, the vane surfaces are developed in smooth sweeping lines from inlet to outlet face of the impeller so as to provide the gradual warping from edges normal to the axis at inlet to edges inclined to the axis at the outlet, as already referred to.

It is also to be observed from Fig. 3 and a comparison of Figs. 2 and 4, that the difference between maximum and minimum radii at outlet is less than at inlet. This difference is due to a reduction of the maximum diameter of delivery openings for the smaller sized and high speed pump here shown. This is not essential, however, and the delivery openings would, of course, be made larger for larger pumps of lower speed.

I have found in the actual use of an impeller conforming to the principles hereinabove referred to, that not only are the flow characteristics of uniform pressures on all radii from inlet to outlet attained, but that the outlet flow is such that constant energy of the water leaving the impeller through the delivery openings is secured even when radii of vanes or vane surfaces differ.

It is apparent from an inspection of Fig. 3, that the water emerges from the impeller, through the outlets 27 between the warped vanes 21, in a somewhat spreading whirling flow, having also, however, energy components in directions inwardly oblique toward the axis of rotation in the general direction of flow due to the warping of the vanes 21. The annular and vaneless whirl chamber 14, formed by the casing unit 29 surround-

ing the impeller 12 and diffuser 13, and extending from the delivery end of the impeller to the entrance side of the diffuser, is shaped in its boundary water-contact surfaces to receive and continue the flow from the impeller without substantial change in direction of flow until the water has advanced well along the chamber walls where, in the advance half portion of the chamber, 5 the walls are curved inwardly on a large arc of curvature to impress upon the flow a gradual change of direction from axial radially outward to axially radially inward. 10 This whirl chamber 14 may, if desired, 15 be made of increasing transverse dimensions toward the outlet end so as to produce some conversion of velocity of flow into pressure, but this result is not required with my diffuser, and in the preferred form of chamber shown, no such result is secured. The 20 main function of the chamber is to enable the water entering therein from the impeller to find its own path under the velocity and direction conditions imposed thereon by the impeller with a gradual change of the general direction of flow from axially radially outward to axially radially inward, as diagrammatically indicated by the flow line 32 projected into the section plane on which 25 Fig. 1 is taken.

Just as the whirl chamber is shaped to receive the flow from the impeller under the velocity and direction conditions imposed thereon by the impeller, so likewise the vanes 35 of the diffuser are shaped in their inlet portions to lie in the line of flow from the whirl chamber and to receive the continued whirling flow therefrom at the angle of flow finally impressed thereon by that chamber, thus presenting a smooth flow without abrupt changes in velocity or direction and avoiding all shock of entrance into the diffuser.

The primary function of the diffuser is to return the flow to a true axial one for 40 delivery into the next impeller of the series, or in the case of the last unit, to deliver the flow into the outlet conduit or discharge cone 33 (Fig. 1) from the pump units proper. An additional function is the conversion of velocity head of whirl into effective pressure head in the discharge although the diffuser vanes are not themselves the essential elements in producing that result.

50 The change from a whirling flow advancing through the whirl chamber from the impeller to a true axial flow presents substantially the same problems of avoidance of energy losses and reductions in outflow by excessive surface friction and eddy currents developed by unequal water pressures along areas normal to the line of flow, presented by the changes from true axial flow imposed by the impeller, and substantially the same general principles are employed in their so-

lution although the mechanical details differ in some respects because of the differing specific functions of the diffuser and impeller.

Viewed along the section plane of Fig. 1, the diffuser may be said to comprise a central cone portion 34, a half section only being shown in that figure, and an outer ring portion 35, providing therebetween the flow passage indicated by the arrow line of flow 70 on Fig. 1. The inner annular face of the ring portion 35 is at a lesser angle of inclination to the pump axis than that of the opposing face of cone 34 so that the annular passage therebetween increases uniformly 80 in width, measured in straight lines between the opposing surfaces in axial planes, from the radially inwardly directed inlet 36 to the axially directed outlet 37. In other words, the flow passage referred to is one 85 between two surfaces of revolution with the passage increasing in transverse area from the inlet to the outlet. It is this uniform increase between the opposing faces referred to, from inlet to outlet, which affects whatever conversion occurs from velocity to pressure in the flow through the diffuser. The diffuser vanes are located in the passage thus generally defined and in fact divide that 90 passage into a plurality of passages, one 95 between each two successive vanes. A section in the plane on which the view in Fig. 1 is taken through any one such passage presents, however, the characteristics just referred to.

100 The detailed characteristics of the diffuser vanes as embodied in the illustrated example of the novel diffuser, will more fully appear from a consideration of Figs. 2, 5 and 6.

Referring first to the plan view of the outlet face of the diffuser, shown in Fig. 5, the flanged face of the ring portion 35 is indicated by the numeral 38 and the central cone portion by the numeral 34. The diffuser vanes 40 start at the inlet end inclined to the pump axis and are brought to axial at the delivery end so that their outlet edges 41 are in a plane at right angles to the axis, as also shown more particularly in Fig. 6 which is a perspective view of the diffuser with the outer ring portion 35 removed so as to more clearly show the vane characteristics. In other words, as in the impeller, the diffuser vanes are warped from normal to the axis to an inclination thereto, the difference being in the direction of warp. In the impeller the vanes are warped from a position where their entrance edges are in a plane normal to the axis at the inlet end to a position where their delivery edges are at an acute angle to any axial plane intersecting said delivery edges at the delivery end, while in the diffuser the vanes are warped from a position where their entrance edges slope in an opposite direction to the 110 115 120 125 130

discharge edges of the impeller and also are at an acute angle to any axial planes intersecting said edges at the inlet to a position where each delivery flow surface is in a plane parallel to the axial plane intersecting the delivery edge normal at the delivery end. And, broadly considered, it may be said that the warping characteristics in the two cases are complementary, because the functions of the impeller and diffuser are complementary, the inlet ends of the diffuser vanes receiving the flow delivered from the outlet ends of the impeller with but little change from the outwardly whirling form imparted thereto by the warping of the impeller vanes and the warping of the diffuser vanes returning the flow to its initial axial direction under the same favorable conditions, including eddyless current, equalizations of water pressures, and uniform head or pressure in the flow throughout the entire area of the outlet, obtained in the functioning of the impeller.

The cooperative relation in their vane characteristics of the impeller and diffuser, as well as the cooperating relation to both of the whirl chambers between them, is shown in Fig. 2, which figure, as previously stated, is a sectional view on the line 2—2 of Fig. 1, looking in the direction of the arrows on Fig. 1. The portion shown on the right hand side of Fig. 2, is taken, it is to be observed, on the lowermost part of the section line 2—2 of Fig. 1, just inside the entrance rim 19 of the impeller (see Fig. 3 for a perspective view of that entrance rim), and at the junction of that rim with the annular member or shroud 18 of the impeller. The portion of the right hand side of Fig. 2 is, therefore, in effect a partial plan view of the entrance face of the impeller, minus the entrance rim. The left hand portion of the sectional view of Fig. 2, that on the upper part of the line 2—2 of Fig. 1, shows a partial end view of the inlet face of the diffuser, the opposite, or outlet face of the diffuser being shown in Fig. 5. The inlet end edges of two impeller vanes 21 are shown in full lines in Fig. 2 with the inlet mouth 25 of an impeller passage formed between them, and also in dotted lines the obliquely inclined end edges 21' of one of these impeller vanes at its outlet end in the outlet face of the impeller, which outlet face is, of course, hidden from view in Fig. 2, but is partially shown in Fig. 4.

Fig. 2 shows also, in partial end elevation and in sections along the section line 2—2 of Fig. 1, the outer casing wall 29, and the whirl chamber 14 formed on the interior thereof. Looking in the direction of the water-flow into the entrance of the impeller as in Fig. 2, the water entering the inlet 25 emerges past the outlet ends 21' of the impeller vanes in a whirling flow in

clockwise direction into the whirl chamber 14 through which it advances in the manner already described to the inlet ends of the diffuser vanes. The partial sectional view along the upper part of the line 2—2 of Fig. 1, presented by the left hand portion of Fig. 2, shows the entrance edges 40' of the diffuser vanes 40 obliquely inclined from the entrance rim 42 of the annular outer member or shroud 35 (see also Fig. 1) to the conical face of the core portion 34 of the diffuser just in advance of the curved entrance rim 43 (see Fig. 1 as well as Fig. 2) of that conical surface. As shown in Fig. 1, and by a comparison of the views of the impeller shown in Figs. 3 and 4 with the view of the diffuser shown in Fig. 6, the inlet edges 40' of the diffuser vanes 40 lie in a plane inclined to the pump axis at substantially the angle of inclination of the outlet edges 21' of the impeller vanes but in opposite direction of inclination. Also, as shown more particularly in Fig. 1, the entrance end edges 40' of the diffuser vanes are disposed in the line of whirling flow (clockwise as the parts are viewed in Fig. 2), from the whirl chamber 14, without any substantial change in velocities or directions of flow. In other words, the impeller forms and delivers the whirling flow, the whirl chamber receives it and in the onward movement of the whirl gradually inclines it from its initial radially outward direction toward the pump axis sufficiently for its reception by the diffuser, thus enabling the use of a diffuser of small diameter in axial line with the impeller.

The diffuser vanes 40 are in warped planes throughout their entire extent from their entrance edges 40' inclined to the axis to axial end terminals 41 in planes normal to the axis as shown in Figs. 5 and 6, and conform to the principles of warped surface and smooth flow lines hereinbefore referred to in describing the vane characteristics of the impeller. In the construction illustrated, the diffuser vanes themselves are not relied on to provide the increasing area of flow passage in successive planes normal to the line of flow required for converting velocity of inlet flow to pressure at the outlet of the diffuser, the diverging opposite wall surfaces of the core member 34 and the shroud or ring member 35 of the diffuser (see Fig. 1), as already stated, being relied on for the reduction in velocity toward the outlet end and consequent conversion of velocity into pressure, but it will be understood that the construction may be such that this conversion is secured in substantial amount by the form of the vanes or by the divergence of the opposite side walls, as shown, or by both. The warping of the diffuser vanes from axial at the outlet end along a conical surface toward the inlet end in directions of

curvature gradually increasing radially outward along that surface, to a disposal of their inlet ends each in a plane inclined to the diffuser axis, does, however, perform important functions in addition to the presentation of the inlet ends of the vanes in the line of flow from the whirl chamber. Important results attained are the accommodation of the higher velocities of flow at the inlet end over the velocities of outflow and the equalization of water pressures throughout each successive area normal to the line of flow from inlet to outlet, thus insuring full capacity of flow without eddy currents, a minimum of surface friction and other energy losses and a constant energy output or pressure head throughout the entire area of the outlets.

What I claim is:

1. In a hydraulic pump, in combination, a casing, an impeller therein forming and delivering the flow in a direction the resultant of outward radial, tangential and axial components, an annular chamber extending from the impeller outlet and providing a vane-free passage for said flow, said chamber having a boundary water-contact surface impressing upon the flow advancing therewith a gradually increasing inward radial component, and a diffuser on the discharge side of said passage in axial alignment therewith, having vanes with their inlet ends lying substantially in the line of flow discharging from said chamber and a surface contour gradually impressing on the flow advancing therewith toward the outlet end a gradually increasing axial component.

2. In a hydraulic pump, in combination, a pump casing, an impeller therein delivering the stream in an advancing flow having a movement of rotation about the pump axis, an annular chamber extending from the impeller outlet and providing a vane-free passage for said flow and a diffuser on the discharge side of said passage having vanes extending about the pump axis from axial at their outlet ends to inlet ends lying substantially in the line of the advancing rotational flow.

3. In a hydraulic pump, in combination, a pump casing, an impeller, vane-free whirl chamber and vane-equipped diffuser in series in axial alignment and providing a continuous flow passage, said impeller forming and delivering the flow into the whirl chamber in an outwardly spreading advancing whirl, said chamber having a contour of flow-contact surface receiving said advancing whirl of flow and gradually impressing thereon a directional change to a form of whirl inwardly converging toward the diffuser inlet, the vanes of said diffuser being inclined at the inlet end to lie substantially in the flow lines of whirl from said chamber.

ber and of a surface contour from inlet to outlet ends producing an axial outflow.

4. In a hydraulic pump, in combination, a pump casing, an impeller in said casing adapted to form and deliver an axially advancing and radially outward whirling flow, a diffuser in axial line with but spaced from said impeller and having vanes of a surface contour from inlet to outlet end arranged to form dividing walls for flow passages extending spirally about the pump axis, said vanes being warped to gradually force the flow inward and tangentially in opposition to the tangential component of the whirl at the inlet end and axially at the outlet end and a reversing chamber between said impeller and diffuser adapted to reverse the radial component of said whirling flow from radially outward to radially inward.

5. In a hydraulic pump, in combination, a pump casing, an impeller and diffuser therein spaced in axial alignment, said impeller having vanes terminating at the delivery end on a peripheral surface of the impeller inclined toward the axis in the direction of the diffuser and with the end edges of said vanes at an inclination to the radial, said diffuser having vanes terminating at their inlet ends on a peripheral surface of the diffuser inclined toward the axis in the direction of the impeller and with the inlet end edges of said vanes inclined to the radial in a direction opposite to the inclination of said impeller vanes and a vane-free chamber concentric with and between said impeller and diffuser and having a boundary flow-contact surface spreading radially outward from said impeller outlet and converging radially inward toward said diffuser inlet.

6. In a hydraulic pump, in combination, an impeller having vanes with their inlet ends in axial planes and proceeding in curved lines gradually radially outward and axially toward the impeller outlet and at an inclination or warp of the vane surfaces from axial to inclined in directions producing a combined axial and radially outward flow, a diffuser spaced from the impeller outlet and in axial alignment therewith and provided with vanes having their inlet ends in planes of inclination to the axis and proceeding in curved lines gradually radially inward and axially to axial planes at the diffuser outlet and a reversing chamber receiving the flow from said impeller axially and radially outward and delivering said flow to said diffuser axially and radially inward.

7. In a hydraulic pump, in combination, an impeller having vanes with their inlet ends in axial planes and proceeding in curved lines gradually radially outward and ax-

- ially toward the impeller outlet and at an 55
inclination or warp of the vane surfaces
from axial to inclined in directions producing
a combined axial and radially outward
flow, a diffuser spaced from the impeller outlet
and in axial alignment therewith and a
vane-free chamber receiving the flow from
said impeller axially and radially outward
and delivering said flow to said diffuser.
- 10 8. A rotary impeller having a core, a
shroud, and a plurality of vanes, the surfaces
of each of which vanes, at intersection with
a plane normal to the impeller axis at the
inlet end of the impeller, form arcs extending
15 from the core to the shroud, said vanes
being arranged spirally between the core and
shroud, and extending in curved lines gradually
radially outward, tangentially, and axially
toward the impeller outlet, the vanes
20 being warped gradually so that at the outlet
the vane ends lie substantially on the surface
of an imaginary cone frustum whose axis is
coincident with the axis of rotation of the
impeller, the slope of said frustum being in-
25 ward toward the outlet end of the impeller.
9. A rotary impeller having a core, a
shroud, and a plurality of vanes, the surfaces
of each of which vanes, at intersection with
a plane normal to the impeller axis at
30 the inlet end of the impeller form arcs ex-
tending from the core to the shroud, said
vanes being arranged spirally between the
core and shroud and extending in curved
35 lines gradually radially outward, tangentially,
and axially toward the impeller outlet, the
vanes being warped gradually so that at the
outlet the vane ends lie substantially on the
surface of an imaginary cone frustum whose
40 axis is coincident with the axis of rotation
of the impeller, the slope of said frustum be-
ing inward toward the outlet end of the im-
peller, each vane end, at the outlet, making
45 an acute angle with an axial plane intersect-
ing such end.
10. A rotary impeller for hydraulic pumps
having opposite inlet and outlet openings
with boundaries of different radii, measured
from the impeller axis, the largest radius of
50 the inlet approximately equalling the small-
est radius of the outlet, the flow passages be-
tween inlet and outlet being provided with
vanes in axial planes to the hub on the inlet
side and extending radially outward and ax-
ially forward toward the outlet in a direc- 100
tion of warp disposing the outlet ends of
the vanes in non-axial planes.
11. A rotary impeller for hydraulic pumps
having opposite inlet and outlet openings
with boundaries of different radii, measured
from the impeller axis, the largest radius of
60 the inlet equalling approximately the smallest
radius of the outlet and the difference
between maximum and minimum radii at the
outlet being less than at the inlet, the flow
passages between inlet and outlet being pro-
65 vided with vanes in axial planes to the hub
on the inlet side and extending radially out-
ward and axially forward toward the outlet
in a direction of warp disposing the outlet
ends of the vanes in non-axial planes. 70
12. A rotary impeller for hydraulic pumps
having oppositely disposed inlet and outlet
openings with annular boundaries of dif-
ferent radii, the largest radius of the inlet
75 equalling approximately the smallest radius
of the outlet, the inlet extending inwardly
to the impeller hub, the flow passages be-
tween inlet and outlet being provided with
vanes in axial planes to the hub on the inlet
80 side and extending radially outward and
axially forward toward the outlet in a direc-
tion of warp disposing the outlet ends of
the vanes in non-axial planes and with their
outlet edges on a slope with the terminal
85 point of least distance from the impeller axis
in advance of that of greatest distance.
13. In a hydraulic pump, a diffuser mem-
ber comprising a cone-shaped core member,
90 an outer annular shroud, and a plurality of
vanes located in the space between the core
and shroud, and extending spirally in said
space so as to form spiral channels between
said vanes, the vanes having their inlet ends
95 lying substantially on the slant surface of
an imaginary cone frustum whose axis is co-
incident with the longitudinal axis of the
diffuser member, the slope of said frustum
being inward in the direction of the pump in-
100 let, each vane end at the inlet making an
acute angle with an axial plane intersecting
such end, the guiding surfaces of each vane
at the discharge end lying substantially in
an axial plane, each vane being warped grad-
ually from its inlet end to its outlet end. 105

In testimony whereof, I have hereunto set
my hand.

HARRY F. BENSON.
